SEWING MACHINE

Joseph H. Pikul, West Newton, Mass., assignor
to The Reece Corporation, a corporation of
Maine

Application February 21, 1944, Serial No. 523,173

3 Claims. (Cl. 112—197)

1

This invention relates to machines for forming stitches in material.

Heretofore, when chain stitches were resorted to in machine sewing, it was necessary to terminate any group of continuous chain stitches with a conventional tying stitch in order to secure the entire group of stitches against unravelling. An example of a sewing machine of this type is shown and described in my prior Patent No. 2,131,387, dated September 27, 1938. While a conventional tying stitch secures a group of chain stitches in a satisfactory manner, its formation by the same instrumentalities which form the chain stitches involves at least a different operation of these instrumentalities, which complicates the machine and accordingly increases the cost of the same.

It is the primary aim and object of the present invention to make provision in a sewing machine for securing a machine-sewn group of continuous chain stitches against unravelling without resorting to a conventional tying stitch and without requiring a different operation of the stitch-forming instrumentalities of the machine.

The invention will be more clearly understood from the following description in conjunction with the accompanying drawings, in which:

Fig. 1 is a greatly magnified bottom view of a piece of material holding a series of chain stitches which are secured against unravelling in accordance with the present invention.

Fig. 2 is a section taken substantially on the line 2—2 of Fig. 1, and illustrates the conventional concatenation of the loops of a chain stitch.

Fig. 3 is a section taken substantially on the line 3—3 of Fig. 1, and shows an intermediate step in securing the last stitch of a group of chain stitches against unravelling.

Fig. 4 is a section similar to Fig. 3, showing the last stitch completed.

Figs. 5 and 6 are sections taken substantially on the lines 5—5 and 6—6, respectively, of Figs. 3 and 4, respectively.

Fig. 7 is a greatly enlarged, fragmentary sectional view of the stitch-securing mechanism of a machine embodying the present invention.

Figs. 8 and 9 are fragmentary sectional views similar to Fig. 7, showing progressive steps in the operation of the mechanism in securing the last stitch of a series of chain stitches.

Figs. 10 and 11 are fragmentary sections taken substantially on the lines 10—10 and 11—11, respectively, of Figs. 7 and 9, respectively.

Fig. 12 shows a modified element of the stitch-securing mechanism of the machine.

2

Fig. 13 is a greatly magnified section through a partly completed, securing stitch obtained with the modified element of Fig. 12, the section being similar to the section of Fig. 5.

Fig. 14 is a section similar to Fig. 13, showing the secured stitch completed.

Fig. 15 is a greatly magnified illustration of a straight seam of chain stitches secured against unravelling in accordance with the present invention.

Fig. 16 is another greatly enlarged, fragmentary sectional view of a part of the stitch-forming mechanisms of the machine.

Fig. 17 is a fragmentary sectional view similar to Fig. 16, showing modified structure for securing chain stitches against unravelling.

Fig. 18 is a fragmentary section taken substantially on the line 18—18 of Fig. 17.

Fig. 19 is a side elevation, partly broken away, of the machine which incorporates the stitch-securing mechanism of the present invention.

Fig. 20 is a plan view, partly broken away, of the machine as shown in Fig. 19.

Fig. 21 is an end elevation, partly broken away, of the machine as viewed from the left in Figs. 19 and 20.

Fig. 22 is an end elevation of the machine as viewed from the right in Figs. 19 and 20.

Fig. 23 is an end elevation similar to Fig. 22, showing certain parts in a different relative position.

Referring to the drawings, Fig. 1 illustrates greatly magnified the back side of a piece of material W in which successive chain stitches 30 are formed. By way of example, these stitches are shown as arranged in zig-zag fashion. The formation of the chain stitches is conventional, the machine which may be used for this purpose providing a reciprocatory and laterally vibratory needle 31 (Fig. 21) and two loopers 32 which alternately cooperate with the needle 31 in the formation of successive chain stitches. Fig. 7 illustrates a step in the normal cooperation of the needle 31 and one of the loopers 32 in the formation of the chain stitches, the looper 32' having seized the thread loop l cast by the needle 31 on its preceding ascent through the hole h in the material, and deflected it into the position shown in Fig. 7 in which said loop is in alignment with the needle in the left end position of its lateral vibration.

After the machine has sewn a group of continuous chain stitches, the needle 31 and the looper 32' will come to rest in the relative disposition shown in Fig. 7 with the last loop l held on

said looper. While the last loop l is thus held on the looper 32', a blade or deflector 33 below the throat plate 34 is linearly moved from the position shown in Figs. 7 and 10 into the position shown in Figs. 9 and 11 to deflect the diverging legs of said loop l . The deflector 33 is provided with a slot 35 (Fig. 10) of a width substantially equal to the thickness of the needle thread t , and a wedge-shaped notch 36 which leads into the slot 35. Hence, on movement of the deflector 33 from the position shown in Fig. 7 into that shown in Fig. 9, the two legs of the loop l are guided toward the slot 35 by the notch 36 and enter said slot one behind the other. In the present instance, the deflector 33 is so coordinated with the looper 32' that the slot 35 in said deflector is in line with the rear leg l^x of the loop l so that, on movement of said deflector from the position shown in Figs. 7 and 10 into that shown in Figs. 9 and 11, said leg l^x enters said slot 35 without engaging a wall of the V-shaped notch 36, while the front leg l^y of the loop l is cammed into the slot 35 by the wall 36' of the V-shaped notch 36. Consequently, the rear leg l^x of the loop l will enter the slot 35 before the front leg l^y is cammed thereinto, with the result that the portions of these legs which extend from the deflector 33 substantially to the material W become superposed with the front leg l^y nearest the material W (Figs. 8 and 9). Since the loop l is being distended while being deflected, and since the saddle thread tension devices (to be referred to hereinafter) of the machine resist with considerable force the drawing of needle thread through the needle while the loop l is being deflected as described, the distending loop l will draw thread from the preceding loop l' (Figs. 7 and 8) until the latter is drawn tight. The rear wall 38 of the slot 35 in the deflector 33 is rounded as shown in Figs. 7 to 9 so as to avoid chafing the thread of the distending loop l . In order to permit the contracting loop l' to close as tightly as possible about the legs of the loop l when the latter is being distended (Figs. 5 and 9), the deflector 33 brings the legs of the loop l preferably as closely as possible to the convergence C of the legs of the preceding loop l' (Figs. 9 and 11). To this end, the deflector 33 is arranged to deflect the legs of the loop l as closely as possible to the material W (Fig. 9), the deflected legs of the loop being received in a cut-away portion 39 of the throat plate 34. To the same end, the deflector 33 is moved in such a direction that the legs of the loop l between the deflector and the material (Fig. 11) pass the convergence C of the legs of the loop l' as closely as possible so that said loop l' may contract into firm wedging engagement with the legs of the loop l without undue restraint from the latter. The contracting loop l' , through intermediation of the legs l^x and l^y of the loop l , also draws the loop l'' , which immediately precedes the loop l' , firmly against the material W (Figs. 3 and 9). Shortly before the deflector 33 reaches the most advanced position shown in Fig. 9, the same brings the rear leg l^x of the loop l into engagement with a knife 40 on the looper 32' (Figs. 9 and 11), whereupon said leg is severed as at 41. On subsequent removal of the material W from the machine, the severed portion of the loop l which is continuous with the needle thread is withdrawn from the material, leaving the severed rear leg l^x of said loop l anchored between the loops l' and l'' (Figs. 4 and 6).

The pull exerted by the distending loop l on 75

the thread of the preceding loop l' is so great that the thread of said loop l as well as of the loop l' is stretched within the limit of its resiliency, and the contracted loop l' draws the loop l against the loop l'' with such force that the engaged portions of said loops are considerably deformed and constricted (Figs. 3 and 5). The thread of the contracted loop l' is in fact stretched to such an extent that the withdrawal therefrom of the severed end of the loop l does not cause any noticeable relaxation of its firm grip on the remaining portion of the severed loop l , the loop l' having sufficient resiliency to contract and hold the adjacent portion of the remainder of the severed loop l deformed and constricted as shown in Figs. 4 and 6. That the loop l' is under permanent tension and does not noticeably relax its firm grip on the severed loop l , even after the withdrawal of the severed end thereof, is evidenced by a very marked cross-sectional constriction of the leg l^x between the loop l' and the material W (Fig. 4) as observed under a microscope. As also observed under the microscope, the cross-over leg l^y of the last stitch is partly embedded in the material W (Fig. 4) in consequence of the permanent tension in the thread of said last stitch. The tied chain stitch shown in Figs. 4 and 6 has defied all ordinary efforts to unravel or even loosen the same, wherefore said stitch serves as, and is in fact, a novel tying stitch which is as well secured against unravelling as a conventional tying stitch.

Whereas the described deflector 33 has a provision (narrow slot 35) for forcing the deflected legs of the loop l into superposed relation along the material W (Fig. 9), a modified deflector 45 (Fig. 12) merely forces the diverging legs of the loop l together. To this end, the deflector 45 has a wedge-shaped notch 46 the bottom 47 of which is rounded. On movement of the deflector 45 in the direction of the arrow 48 in Fig. 12, the diverging legs of the loop l on the looper 32' will, besides being deflected, also be forced into side-by-side engagement with one another by the rounded bottom 47 of the notch 46, resulting in the disposition of the legs of loop l in the contracted loop l' as shown in Fig. 13. After severance of the loop l and withdrawal of the severed end thereof from the contracted loop l' , the remaining end of the severed loop is wedged against the contracted loop l' (Fig. 14) and against the preceding loop l'' in much the same fashion as shown in Figs. 4 and 6.

Fig. 15 shows the novel tying stitch applied at the end of a straight seam of chain stitches 50, the contracted loop 51 of the last stitch firmly wedging the remaining end 52 of the last severed loop against the loop 53 which immediately precedes the loop 51. In view of the preceding, detailed description of the formation of the novel tying stitch at the end of a zig-zag seam of chain stitches, the formation of the same tying stitch at the end of a straight seam of chain stitches is too obvious to require further explanation.

Figs. 16 and 17 disclose a modified mode of tying the last one of a series of chain stitches. The machine used for forming these stitches may be like the one used for forming the stitches 30 in Fig. 1, and comprise a reciprocating and vibratory needle (not shown) carrying needle thread t , and a pair of alternately operative loopers of which one is shown at 55. After the sewing instrumentalities of the machine come to rest with the needle retracted and the looper 55 in the position

shown in Fig. 16 and holding the last loop 56, a deflector 57 underneath the throat plate 58 is moved in the direction of the arrow 59 in Fig. 18 to deflect the front leg 56' in the manner best shown in Fig. 17, thereby distending the loop 56. The deflected leg 56' of the distending loop 56 forces the preceding loop 60 against the material W and the convergence of the legs of the loop 56. The distending loop 56, being unable to draw needle thread through the needle thread tension devices (not shown) of the machine, must draw thread from the preceding loops 60 and 61. Since the loop 60 is prevented from contracting by the deflected leg 56' of the last loop 56 (Fig. 17), the latter will draw thread from the loop 61 which immediately precedes the loop 60. The ensuing contraction of the loop 61 draws the loop 60 into firm wedging engagement with the material W and the convergence of the legs of the loop 56 and at the same time forces said loop 61 toward the convergence of the legs of the last loop 56 (Fig. 17), so that, after severance of the last loop 56 and withdrawal of the severed end of said loop from the material, the end of the severed loop remaining in the material is held fairly securely between the loops 60 and 61. The deflector 57 has preferably an inclined cutting edge 62 (Fig. 18) which engages and severs the rear leg 56' of the loop 56 as at 63 when the front leg 56' thereof is deflected as shown in Figs. 17 and 18. A last stitch tied in this fashion, while not as firmly secured as the previously described stitch shown in Fig. 4, for instance, is nevertheless satisfactory for many purposes.

Figs. 19 and 20 show an example of a machine which may be equipped with mechanism to form the novel tying stitch shown in Figs. 4 and 6, for instance. This machine is a button hole sewing machine of the type known as "straight hole" machine, described, for example, in Patents Nos. 714,284, November 25, 1902; 749,776, January 19, 1904; 1,088,652, February 24, 1914; 1,402,073, January 3, 1922; and 1,483,307, February 12, 1924. The machine comprises a bed 65 from which rises a standard 66, carrying an overhanging arm 67 spaced above the bed. The material or work W is carried by a work clamp or holder comprising a clamp plate 68 and cooperating clamping arms 69, said work holder being movable as a unit over the bed, by mechanism not shown, in order to position the stitches along the sides of the buttonhole. The stitch-forming instrumentalities comprise the previously mentioned, eye-pointed needle 31 above the work and cooperating loopers or equivalent under thread handling devices 32 below the work, the throat plate 34 being carried by the bed 65 and having an opening 10 through which the needle operates. The needle 31 is carried by a needle bar 71 which is longitudinally and vertically reciprocated, by means generally indicated at 72, in a needle bar guide 73, means (not shown) being provided for oscillating said needle bar alternately in opposite directions transversely to the direction of feed of the work clamp between successive strokes of the needle to position the depth stitches. The thread t from a suitable source passes, through a take-up 74 and suitable tension devices 75 and 76, to the needle eye, whence it passes through the work and throat plate to the loopers 32. The thread tension device 75 may be a thread clamp which is preferably closed during the setting of the last stitch so as to cause the tying of the last stitch with a maximum force. A main shaft 77, journalled in suitable bearings in the bed, has power applied there-

to by a belt 78 alternatively engageable with fast and loose pulleys 79 and 80 under the control of a belt shifter 81. The belt shifter 81 constitutes an extension of a stop member or arm 82 carried by an oscillating and longitudinally movable rock shaft 83, mounted for oscillation and limited longitudinal movement in the bed 65. Slidably mounted in the stop arm 82 is a stop element or bolt 84, normally urged toward the right in Figs. 22 and 23 by a spring 85. At its end the bolt 84 is formed with a nose 86 which, when the shaft 83 is in the longitudinal position to cause the belt shifter 81 to engage the belt 78 with the loose pulley 80, is in the path of movement of a cam 87 (Figs. 22 and 23) which is fast on the shaft 77, said cam having a concentric portion a, a rise b, a notch c and a stop shoulder d, arranged to engage the nose 86 in the order named when the shaft is rotated in the direction of the arrow 88 in Figs. 22 and 23. The nose 86, when in the path of movement of the cam 87, is held in engagement with the periphery of the latter by a spring-pressed plunger 89 carried by the upright 66 and engaging the stop arm 82, said plunger tending to turn said arm and the rock shaft 83 in a clockwise direction as viewed in Figs. 22 and 23, and thereby press the nose 86 against the periphery of the cam 87.

A buttonhole cutter 90 is carried by a lever 91, journaled on a short stud shaft 92 supported in the bed, said lever having an arm 93 carrying at its end a sleeve 94 in which is journalled a stud 95, having at one end a sleeve portion 96 which receives a stud 97 extending inwardly from the stop arm 82.

The construction, arrangement and mode of operation of the parts above referred to, and certain associated parts, are, or may be, substantially as more fully described in the above-mentioned patents. Associated with the sliding rock shaft 83 is a spring 100 (Fig. 20) surrounding said shaft and interposed between a collar 101 thereof and one of the bearing brackets or ears 102 in which said shaft is mounted, said spring tending normally to move said shaft toward the right in Fig. 20 into the position shown in the drawings, in which the belt 78 is engaged with the loose pulley 80 and the nose 86 of the stop bolt 84 is in the path of movement of the cam 87. To start the machine, a starting lever 103 is operated to move the shaft 83 toward the left in Fig. 20, thereby shifting the belt 78 from the loose pulley 80 to the fast pulley 79 and moving the nose 86 out of the path of movement of the cam 87, said shaft being retained in this position by engagement of a detent 104 with a recess 105 therein. The detent 104 is controlled by mechanism (not shown) associated with the feeding means for the work clamp and adjustable in accordance with the length of the button hole to be sewn, the arrangement being such that just before the conclusion of the sewing cycle, and at about the beginning of the last stitch-forming cycle, the detent 104 is withdrawn from the notch 105, whereupon the spring 100 causes the shaft 83 to be restored to its normal position, thereby shifting the belt 78 from the fast pulley 79 to the loose pulley 80 and bringing the nose 86 into the path of movement of the cam 87. During the formation of the last stitch, the machine runs under its own momentum and the nose 86 follows the periphery of the cam 87. As said nose is engaged by the rise b of said cam, the stop arm 82 is lifted against the action of the spring-pressed plunger 89 into the 75 position shown in Fig. 23. This lifting of the stop

arm 82 operates, through the stud 87 and its connection with the arm 83 of the lever 81, to advance or depress the button hole cutter 88 and cause the same to cut the button hole slit. Thereafter, the nose 86 drops off of the rise b of the cam 87 and, under the influence of the spring-pressed plunger 89, enters the notch c as shown in Fig. 22, this movement causing the button hole cutter 88 to be retracted or raised to its original normal position. The nose 86 is thereupon immediately engaged by the stop shoulder d, thereby positively stopping the machine at the completion of the final stitch, the stopping impact being cushioned by a yielding of the bolt 84 toward the left in Fig. 22 against the compression of the spring 85.

In accordance with the present invention, a loop deflector such as the deflector 33 in Figs. 9 and 10, for instance, is guided in ways in the bed 65 immediately below the throat plate 34 and between the latter and the loopers 32 (Figs. 19 and 21). At the completion of the last stitch-forming cycle, and substantially coincidentally with the stopping of the machine, said deflector 33 is moved, by means to be described, from its normal retracted position shown in Fig. 20 in the direction of the arrow 110 in said figure to deflect, and thereby distend, the last loop l which, at this time is held by one of the loopers 32 and extends from the work W about said looper to the needle 31 as shown in Fig. 21. The deflection and simultaneous distention of the loop l by the deflector 33 results in the setting of the last stitch in the manner previously described and shown in Figs. 3 and 5. The looper which holds the last loop l also preferably carries a knife or cutter 40' which may be like the cutter 40 on the looper 32' in Fig. 9 and severs the rear leg of the loop l toward the end of its distention by the deflector 33. On subsequent removal of the material W from the machine and according withdrawal of the severed end of the loop l from the material, the last stitch is completed, and this stitch is the same as, and has all the described characteristics of, the novel tying stitch shown in Figs. 4 and 6.

The deflector 33 is provided with a socket 111 (Fig. 21) to receive a rounded end 112 of an arm 113 which is fast on one end of a rock shaft 114,

journalled in suitable bearings in the bed 65 and having secured to its opposite end an arm 115 (Figs. 20 and 22). Pivotaly connected to the arm 115 is a link 116 guided on the outer side of the bed 65 on a screw 117 projecting from said bed and received in a slot 118 in said link. At its other end the link 116 is formed with a notch 119 adapted to be entered by a nose 120 on a collar 121 secured to the stop bolt 84.

When the nose 86 of the stop bolt 84 enters the notch c in the cam 87 under the influence of the spring-pressed plunger 89, as above explained and as shown in Fig. 22, the nose 120 enters the notch 119. Thereafter, when the stop bolt 84 yields under the impact of the shoulder d on the nose 86, the link 116 is moved toward the left as viewed in Fig. 22, thereby turning the shaft 114 and operating the deflector 33 as described.

The above described tying stitch and method of making the same are not claimed herein, being covered by the claims of a divisional application Serial No. 553,527, filed September 11, 1944.

I claim:

1. In a sewing machine, the combination with a work support, a reciprocatory needle and a looper cooperating therewith in the formation of chain stitches in material, of a member between said looper and the work support movable from adjacent a first thread loop held on said looper toward and beyond the immediately preceding, spaced thread loop in the material and adapted to engage and deflect both legs of said first loop to distend the same so that said immediately preceding thread loop is drawn toward the material and into wedging engagement with the legs of said first loop.

2. The combination in a sewing machine as set forth in claim 1, in which said member has a V-shaped notch to engage and force together the diverging legs of said first loop.

3. The combination in a sewing machine as set forth in claim 1, in which said member has a slot of a width substantially equal to the thickness of the thread and a V-shaped notch leading into said slot and adapted to engage and force the diverging legs of said first loop into said slot.

JOSEPH H. PIKUL.
